UNITED STATES PATENT OFFICE.

ANDREW J. WOODCOCK, OF WILMETTE, ILLINOIS.

FUEL-OIL BURNER.

Application filed November 30, 1925. Serial No. 72,070.

This invention relates to a novel and improved fuel oil burner and more particularly to a generator for use with an oil burner to vaporize the oil.

5 In my co-pending application, Serial No. 675,310, filed November 17, 1923, I have disclosed a burner comprising a generator of the general type referred to above and to which the oil is fed by gravity or other suitable means and permitted to drop or flow in 10 a thin stream into the generator where it is heated and thus vaporized. The vapor or gas is permitted to escape by its own pressure acting against the weight of a cap used to 15 close a ground seat. The gas escaping from the generator is directed downwardly thereabouts and ignited to supply the heat which is necessary to generate the gas from the oil in the generator, this result being achieved 20 by a current of air directed downwardly on the generator.

It is the object of my invention to improve upon the construction of the generator briefly described above by providing a surface therein on which the oil may be received and spread out in order that it may be more 25 efficiently heated and thus more quickly reduced to gas.

A still further object is to provide a generator of such form that the gas escaping therefrom may more nearly surround the entire generator and in particular will come in contact with the surface of the generator over which the oil has been spread.

30 A still further object is to simplify the construction of the generator disclosed in my aforesaid co-pending application, by materially reducing the number of parts therein.

A still further object is to provide a generator having a generating surface over 40 which the oil is spread, and which surface is of a large area, without materially increasing the size of the generator as a whole.

In the drawing in which I have shown 45 selected embodiments of my invention,

Fig. 1 is a vertical sectional view through one form of my improved generator;

Fig. 2 is a similar section showing a modification and

50 Fig. 3 is similar view showing still another modification.

Referring now to the drawing and particularly to Fig. 1, the numeral 1 designates a base plate on which may be supported one or more generators, the number being a mat-

ter of choice, as fully brought out in my aforesaid co-pending application. In the instant application I have limited the disclosure to one generator, as it is to the details of the generator that the present invention relates. Supported on the base plate 1 in any suitable manner is my generator body 2 which I have shown as formed with a chamber 3 for the generation of gas from oil which is fed into said chamber. I provide 60 the generator with a flat bottom 4 substantially circular in form, whereby the chamber 3 is provided with a flat bottom surface 5. Preferably integral with the bottom 4 is an upwardly inclined flange 6 curved vertically, 65 as shown, and terminating in a preferably ground seat 7 to support a weighted cap 8. The cap is substantially surrounded by the branch 9 of a dome through which air is supplied to the generator in a manner fully 70 set forth in my aforesaid co-pending application.

Oil or other liquid fuel is supplied to the generator by means of a pipe 10 passing through the base plate 1 and terminating 80 within a recess 11 in the weighted cap 8. A suitable space 12 is left between the end of the pipe and the upper end of the recess 11 and there is a clearance between the outside of the pipe and the surface of the recess for 85 a purpose which will presently appear. It will also be noted that the downwardly extending portion 13 of the weighted cap, which may conveniently be cast integral with the upper portion and be in the form 90 of a cylindrical extension, terminates a substantial distance from the bottom surface 5 of the generator.

In operation, oil or other suitable liquid fuel is admitted through the pipe 10, it 95 being understood, of course, that the supply may be regulated by any suitable valve 14. The amount of oil permitted to enter the pipe 10 is sufficient to reach the top of the pipe and enter the space 12. The clearance 100 between the outside of the pipe 10 and the walls of the recess 11 is properly designed so that the oil will then drip down the outside of the pipe or run down in a thin film. As it reaches the bottom of the cylindrical extension 13, the oil will drop on to the surface 5 and spread out thereover. As disclosed in my aforesaid co-pending application, I provide a trough 15 immediately 105 under the generator to receive a priming 110

charge of fuel. This fuel is ignited in the initial operation of the burner and it will be seen that with the form of generator I have herein disclosed, the oil spread over the 5 surface 5 will rapidly vaporize and the resulting gas will fill the generator. When this gas reaches a certain pressure, it will lift the weighted cap 8 and flow out at the 10 point where the weighted cap rests on the ground seat 7. The current of air flowing through the branch 9 of the dome will direct the gas downwardly around the curved sides 6 and under the bottom 4. The downward current of air tends to increase the force of 15 the gas, which is initially directed downwardly by the overhanging lip 16 of the weighted cap 8, unless the force of the gas happens to be greater than the force of the air, in which case the force of the gas would 20 form a suction, tending to draw the air more rapidly from the dome. In either case, the result is that the gas is a substantial distance from the point where it leaves the generator before it is ignited, thus preventing the formation of carbon at that point, and insuring 25 that the gas is well mixed with the air so as to give practically complete combustion, the flame being very clean and varying in color from blue to white, in actual practice. The flame will follow the course outlined above, which the gas takes, and follow the surface of the generator, a substantial part of the flame passing under the bottom thereof, thereby supplying heat to 30 the bottom surface 5 which I choose to term the generating surface. It will also be seen that the flame which contacts with the side 6 of the generator will also aid in heating the gas within the chamber by conducting 35 heat to the bottom 4 and thus to the generating surface 5, and also by heating the gas which rises from the generating surface, thus maintaining it in its heated condition until the time when it leaves the generator 40 to become ignited. I have found that the oil, as it strikes the heated generating surface, is immediately reduced to gas.

Referring to Fig. 2, this figure shows another form which my invention may take, 50 and it provides an increase in the size of the generating surface, at the same time reducing the size of the generator as a whole. In this form, the generator is made in the shape of a hollow truncated cone having the bottom 4 of substantially greater diameter than in the form shown in Fig. 1. The conical side 17 provides a surface down which the flame is directed in the same manner in which it is directed down the curved side 6. It will be seen that the chamber in this 55 form is somewhat smaller than in the form of Fig. 1, but the generating surface 5' is much larger and I have found that the area of this surface governs the capacity of the generator. By making the bottom 4 suffi-

ciently thin, I provide a surface which is rapidly heated by the flame which follows the surface of the generator around under the bottom 4, thus causing immediate gasifying of the oil which drops thereon. This 70 form is otherwise like that of Fig. 1 in all respects.

In Fig. 3 I have shown a still further modification of my invention, in this case the bottom 4 being of substantially greater diameter than those in either Figs. 1 or 2, and being joined to the conical side 18 by means of a flattened annular surface 19, spaced from the bottom 4, but generally parallel thereto. By this means the surface 5'' is 80 provided and because of its greater area, the capacity of the generator is greatly increased, without materially increasing the size of the generator as a whole. In all other respects this form of the invention is 85 the same as that shown in Fig. 1 and it operates in the same manner. The ignited gas will not only heat the oil which falls upon the generating surface, by contact of the flame with the bottom 4, but also by 90 contact of the flame with the surface 19. It will be seen that in all forms of my invention the generating surface is pitched downwardly away from the center, so as to convey the oil dropped thereon toward the outer 95 limits of the surface, and while the gas is generated from the oil almost instantly upon its striking the generating surface, nevertheless, by providing the surface 19 so as to heat the oil which reaches the outer limits 100 of the generating surface from both top and bottom, I insure that this oil shall be thoroughly gasified, and this is particularly true in the initial operation of the burner, when there may be a certain amount of oil 105 collected on the generating surface. At this stage, such oil will be collected between the surface 4 and 19 in the modification of Fig. 3 and will be most effectively heated because 110 of the contact of the flame with the surfaces 19 and 4.

From the above it will be seen that I have provided a generator which will be extremely efficient in operation, immediately reducing to gas the oil which is fed thereto, automatically controlling the escape of the gas and burning the gas exteriorly of the generator at a place where it will most efficiently supply the necessary heat to cause continued generation of gas within the generator.

Furthermore, it will be apparent that I have reduced the number of parts in the generator to a minimum. By making the cap with its downward extension in one piece, the cost of production and assembling 125 is materially reduced.

I am aware that changes in the form, construction and arrangement of parts may be made without departing from the spirit and without sacrificing the advantages of the 130

invention and I reserve the right to make all such changes as fairly fall within the scope of the following claims.

I claim:

- 5 1. A generator for vaporizing the fuel oil for an oil burner and comprising a body open at the top, having a substantially flat bottom, and inclosing a generating chamber, the bottom of the body being accessible to
- 10 the flame from the generator, an oil fuel supply tube projecting through the bottom of the body and through the chamber therein to the top of the body, and a weighted cap arranged to rest upon the open top of
- 15 the body to close the same and having an extension projecting into the vaporizing chamber and provided with a recess to receive the oil fuel supply tube, there being a clearance between the walls of said recess and the tube at the side and at the top thereof.
- 20 and the tube at the side and at the top thereof.
2. A generator for vaporizing the fuel oil for an oil burner and comprising a body open at the top, having a substantially flat bottom, and inclosing a generating chamber, an oil fuel supply tube projecting through the bottom of the body and through the chamber therein and to the top of the body, and a weighted cap arranged to rest upon

the open top of the body to close the same 30 and having an extension projecting into the vaporizing chamber and provided with a recess to receive the oil fuel supply tube, there being a clearance between the walls of 35 said recess and the tube at the side and at the top thereof, the wall of the body being inclined outwardly from the open top of the body towards the bottom of the body.

3. A generator for vaporizing the fuel oil for an oil burner and comprising a body 40 open at the top, having a substantially flat bottom, and inclosing a generating chamber, an oil fuel supply tube projecting through the bottom of the body and through the chamber therein and to the top of the body, 45 and a weighted cap arranged to rest upon the open top of the body to close the same and having an extension projecting into the vaporizing chamber and provided with a recess to receive the oil fuel supply tube, there 50 being a clearance between the walls of said recess and the tube at the side and at the top thereof, the wall of the body being inclined outwardly from the open top of the body towards the bottom of the body, the cap 55 having an annular lip which projects beyond the edge of the open end of the body.

ANDREW J. WOODCOCK.
